ROOFING COMPOSITION

Orlie Howard, Gibson City, Ill.

Application December 11, 1940, Serial No. 369,547

6 Claims.

(Cl. 108—7)

This invention relates to roofing construction and it is one of the principal objects of this invention to provide a roofing composition which will be simple in construction, highly efficient in use and economical in manufacture.

It is another object of the present invention to provide a roofing construction with lap joints with the flanges of the roofing material reinforced by metal strips.

Another object of the invention is the provision of a roofing composition comprising units having flange portions provided with a light gauge metal strip embedded therein to reinforce the flange portion and rigidify the lap joints resulting from an interlocking relationship with the flange portions of adjoining units.

A further object of the present invention is the provision in roofing construction of flange portions which will interlock and overlap with like flange portions of adjacent units with the flange portions provided with metal strips adhered thereto to reinforce the crease lines at the flanges and rigidify the resulting lap joints provided by two interlocking units.

A still further object of the invention is to provide a dry lap joint in roofing construction which will provide a tight seal and assure against seepage of heavy rains and like weather elements.

It is a still further object of the invention to provide a roofing construction with lap joints having a relatively rigid reinforcing member formed therewith to provide a solid seam which will withstand the stresses of heavy winds to assure against any removal of the roofing material by reason of wind pressure and the like.

Other objects of this invention will appear more fully as the description proceeds in view of the drawing in which:

Fig. 1 is a fragmentary perspective view of a roof covered with roofing composition embodying my present invention;

Fig. 2 is a fragmentary perspective view illustrating one form of roofing units with which my present invention is adapted to be associated;

Fig. 3 is a fragmentary perspective view of a portion of the preferred form of my roofing construction with a part thereof laid back to expose a metal strip which forms a part of my invention;

Fig. 4 is a vertical sectional detail view to enlarged scale through the preferred form of the lap joint provided by my construction;

Fig. 5 is a fragmentary perspective view of a modified form of my invention; and

Fig. 6 is a vertical sectional detail through a lap

joint resulting from the modified form of my construction, illustrated in Fig. 5, to enlarged scale.

Referring to the drawing, 10 indicates a unit of roofing composition which is provided with flanges 11 adapted to be bent back upon the unit along crease lines 12. Each of the units 10 is adapted to interlock with adjacent units as illustrated in Fig. 2 by folding the body flanges 11 upon each other to provide a lap joint 13.

10 The preferred form of my invention is best illustrated in Figs. 3 and 4 wherein there is shown a body 14 of roofing material comprising two plies 15 and 16 of the conventional composition roofing material. At the flange portions 11 there is provided a light gauge metal strip 17 which is formed with a crease 12' corresponding to the crease 12 in the roofing material 14. This metal strip comprises two portions 18 and 19 divided by the crease 12', each of which portions are equal in width so that the portion 18 will span the width of the flange 11 while the portion 19 will extend into the body 14 a distance substantially equal to the width of the flange 11. This metal strip is embedded in the body 14 when the roofing material is manufactured and is so positioned with respect to the body as to form a part thereof.

Each of the portions 18 and 19 are provided with perforations 20 which are adapted to align with each other when the flange 11 is bent back upon the body 14. When two adjacent units 10 are joined the flange portion 11 of each unit is adapted to fit into the U-shaped lap provided by the flange 11 of the adjacent unit of the corresponding section of the body 14 thereof. This is best illustrated in Fig. 4 wherein the perforations 20 of each of the sections 18 and 19 of corresponding metal strips are shown in alignment to provide a passage for a fastening means 21 in the form of roofing nails or the like.

It is to be particularly pointed out that when the lap joint 22, illustrated in Fig. 4, is formed there is no cement or other adhesive coating applied to the interlocking flanges 11 and that by reason of the relative rigidity of the metal strip 17 there is a uniform distribution of the binding effect provided by the head 21' of the nails 21 along the lap joint. This uniformity of bond results in a tight seam throughout the length of the lap joint 22 to prevent the seepage of dampness or water into and underneath the roofing units 10.

It is further pointed out that as seen in the cross sectional view, Fig. 4 the reinforcing effect resulting from the metal strip embedded

along the adjoining edges of adjacent units, the binding force of the head 21' of the nails is also distributed transversely of the joint 22 thereby assuring that the free end 23 of the joint will at all times be held in close proximity to the underlying roofing unit 10 adjacent thereto. By reason of the rigidifying effect that the metal strip has upon the lap joint the top fold terminating at the edge 23 is not pliable to the same extent as ordinary lap joints without metal reinforcing and by reason thereof this upper extending fold terminating at 23 will not be readily moved by wind stress but rather will withstand the forces of winds against a lifting action at the lap joints.

In the modified form, illustrated in Figs. 5 and 6, I have shown a body 25 comprising a single layer of roofing material which has adhered thereto a metal strip 17 identical to the strip illustrated in Figs. 3 and 4. This metal strip is adhered to and pressed into engagement with the roofing material 25 so as to form a part thereof thus providing a finished product with a reinforced edge portion ready for appliance upon roofs to be covered. As seen in Fig. 6 this modified form provides a lap joint 26 identical to that shown in Fig. 4 with the exception that there is but a single layer of roofing composition adjacent each layer of metal reinforcing. The lap joint provided by this form has all the benefits and attributes of the preferred form and like the latter will provide a durable interlocking seal at the interconnecting joints of the adjoining units.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having thus described my invention, what I claim as new and desire to protect by Letters Patent is:

1. In a composition roofing comprising a flexible cover having a body with a crease line formed parallel to and spaced from its edge portions, said edge flanges being bent back upon the body in U shape with abutting edge flanges bent alternately under and over their respective body and interlocking with each other, means for fastening said edge flanges to a surface to be covered, the combination with said edge portion of a metallic sheet embedded in said body along said edge portions to reinforce the latter and to coat with the fastening means to provide a seal throughout the interlocked edges.

2. In lap joints for roofing material comprising a flexible surface sheet having an edge portion folded back upon itself to provide a U-shaped flange portion, one U-shaped flange portion being formed above and the other below its respective surface sheet and with the edge portion of each sheet arranged in interlocking relation with a like edge portion on an adjacent sheet, a metallic sheet embedded in said flange portion and extending partially into said surface sheet to reinforce the fold aforesaid and to rigidify the interlocking edge portions when the

latter are nailed down upon the surface covered.

3. In a roofing composition, the provision of a plurality of base sheets having crease lines along their edges to form flange portions, metal strips bridging the crease lines and extending into the base sheet a distance substantially equal to the width of said flange portions, said flange portions being bent back upon their respective base sheets and arranged between the flange portion and body of an adjacent sheet to provide an interlocking relationship between the metal strips, said interlocking metal strips coacting to reinforce the connection between adjacent base sheets and affecting a uniform seal therebetween.

4. In a roofing composition, the provision of a plurality of base sheets each having crease lines along their edges to form flange portions, metal strips bridging the crease lines and extending into the base sheet a distance substantially equal to the width of said flange portions, said flange portions being bent back upon their base sheets to form U shaped edges, the flange portion of each base sheet being disposed within the U shaped edge of the adjacent base sheet to interlock the metal strips thereof, said metal strips having perforations formed therein, and fastening means extending through said flange portions and perforations to affix said roofing composition on a surface to be covered.

5. In a roofing composition, the provision of a plurality of base sheets having crease lines adjacent their edges to form flange portions, metal strips adhered to said base sheets and bridging the crease lines and extending into the width of said flange portions, said flange portions and metal strips being bent back upon their respective base sheet along said creased line to provide U shaped edges, the U shaped edge of adjacent sheets being alternately above on one sheet and below on the other with the flange portion of the upper sheet disposed in the confines of the lower U shaped edge and the flange portion of the lower sheet disposed within the confines of the upper U shaped edge, headed fastening means extending through said flange portions, said metal strips coacting with each other and said headed fastening means to provide a uniformly interlocked seal.

6. In a roofing composition comprising a base sheet formed to provide an interlocking lap joint with an adjacent base sheet, said lap joint including a flange portion on said base sheet, a metal strip formed integrally with said base sheet and extending over said flange portion and into the base sheet a distance equal to the width of said flange portion, said flange portion being bent back upon the base sheet and overlying the flange portion of an adjacent base sheet, said adjacent base sheet being bent back upon its flange portion to overlie said flange portion of the underlying base sheet, said metal strips coacting with said flange portions to provide a ridged rib, perforations formed in said metal strips, said perforations of one metal strip aligning with the perforations of the adjoining metal strip, and fastening means arranged in aligned perforations for attaching said roofing composition to the surface covered.

ORLIE HOWARD.
